SIGNORS TO AMERICAN OPTICAL COMPANY, OF SOUTHERBRIDGE, MASSACHUSETTS,
A VOLUNTARY ASSOCIATION OF MASSACHUSETTS.

OPHTHALMIC MOUNTING.

Application filed November 6, 1924. Serial No. 748,157.

This invention relates to improvements in ophthalmic mountings, and has particular reference to an improved temple construction and an improved method of producing 5 the same.

An important object of the invention is to provide an improved temple having a non-metallic covering formed of tubing having different cross sectional areas at different 10 portions of its length.

Another object is to provide such a device wherein different cross sectional areas are produced by the expansion of a portion of straight tubing.

15 Another object is to provide such a device having a tubular covering of non-metallic material expanded at certain points and reinforced by shape retaining plugs.

Still another object is to provide an improved process for the production of such 20 devices.

With these and other objects in view the invention resides in the novel features of construction, combination and arrangement 25 of parts and the steps in the improved process hereinafter set forth, illustrated in the accompanying drawings, and specifically pointed out in the appended claims.

In the drawings forming a part of this 30 application, and wherein similar reference characters are used to designate corresponding parts throughout the several views:

Figure 1 is a side elevation of a temple embodying the invention;

35 Figure 2 is a side elevation of a non-metallic tube and illustrates one step in the process;

Figure 3 is an end elevation thereof;

40 Figure 4 is a plan view of the metallic core;

Figure 5 is a detail sectional view through the shape retaining plug;

45 Figure 6 is a view partially in section illustrating the tube, core and plug in assembled relationship;

Figure 7 is a fragmentary sectional view through the end of the temple, and showing how the end of the tube is shrunk over the plug;

50 Figure 8 is a fragmentary elevation of the

end of the temple after it has been formed to the proper shape;

Figure 9 is a plan view showing the temple tube provided with a helical cut;

Figure 10 is a side elevation illustrating 55 the next step in the forming of a side portion of the temple;

Figure 11 is a transverse sectional view on the line 11—11 of Figure 10;

Figure 12 is a side elevation of a modified 60 form of temple embodying the invention;

Figure 13 is a transverse sectional view on the line 13—13 of Figure 12;

Figure 14 is a side elevation of a tube 65 used in the construction of another form of temple;

Figure 15 is a longitudinal sectional view through the tube illustrated in Figure 14 and the parts assembled with it;

Figure 16 is a side elevation of a temple 70 so formed, and

Figure 17 is a transverse sectional view on the line 17—17 of Figure 16.

Referring particularly to Figure 1, it will be seen that our improved temple comprises a substantially straight side portion 20, having a hinge connection 21 at its forward end, and having its rear end bent as at 22 to form an ear engaging loop. The side portion 20 and the ear engaging loop 22 75 are formed from a continuous piece of tubing 23, which is preferably of a non-metallic material, such as zylonite. One end of the tube 23 is expanded, as at 24, to produce a larger cross sectional area than the main body portion, the method of expansion being to heat the tube and force the end over a tapered mandrel for the desired length.

We next produce a metallic core member 90 which has a main body portion 25 formed of substantially inflexible metal wire, to the forward end of which is secured the hinge connection 21 of any suitable form. Adjacent the forward end the wire 25 is flattened, as at 26, or it may be provided with barbs 95 or any other arrangement whereby the core may be securely anchored in the non-metallic tube. Rearwardly of the body portion 25 is a wire cable 27 which provides a suitable degree of flexibility, while still maintaining 100

the necessary resiliency so that the whole when assembled will retain its proper shape. The extreme rearward end is preferably provided with a screw thread as at 28, which 5 may be secured within a bore 29 formed in a pear-shaped plug member 30. The plug member 30 is preferably formed of the same non-metallic material as that of the tube 23 and of a suitable size so that it may be conveniently introduced into the enlarged end 10 24 of said tube.

After these parts have been produced the metallic core is inserted into the tube 23, as clearly shown in Figure 6, and the plug member 30 is secured in the enlarged portion 24 by cementing the same in place. The parts are so proportioned that when they are assembled as shown in Figure 6, the extremity of the enlarged portion 24 will extend 15 slightly beyond the plug member 30, whereupon by heating the same, such as by dipping in hot water, the extremity of the tube 23 will be shrunk, as shown at 31 in Figure 7, so as to completely embed the plug member 30 and conceal it from view. After 20 the extremity of the tube has been thus shrunk it is placed in a pair of dies and molded to the required finished shape, or in place of molding it may be finished off in a 25 lathe or other suitable machine tool.

The next step in the manufacture of our temple is to provide a portion of the non-metallic tube with a helical groove, as indicated at 32 in Figure 9. This helical groove 35 is disposed intermediate the two ends, and usually rearward of the longitudinal center. This helical groove in the tube provides suitable flexibility and at the same time maintains a smooth finished surface on the outside of the tube after the ear loop is bent to 40 the required shape.

We next preferably flatten the side portion 20 of the temple into an elliptical cross section, as best shown in Figures 10 and 11, 45 whereby the rigidity of the side portion in the vertical plane is increased so as to provide a much stronger mounting and one of a neater appearance than is possible from a plain circular tube. After the parts have 50 been thus assembled and shaped, the flexible portion 32 is bent into the required form to produce an ear loop, as shown in Figure 1.

In Figure 12, we have shown a modified form of temple wherein the side portion 20 55 is provided with the usual hinge member 21, as in the previous embodiment, the principal difference being that the temple is somewhat shorter than that shown in Figure 1, and the end thereof is given a small offset as at 33, 60 whereby an ear engaging portion is produced. Also in this form the enlarged extremity 34 is given an oval shape, as shown in Figure 13, instead of leaving it in a round cross section shape, as in the previous form.

65 Referring particularly to Figures 14, 15,

16 and 17, we have shown still another modification whereby we may produce a larger temple, such as used in connection with the heavy all zylonite frames. In this form we provide a non-metallic tube 35 and expand both ends of the tube as at 36 and 37, the amount of expansion at each end being variable according to the design. We then provide a metallic core 38 and a non-metallic plug 39, which is adapted to be received in the expanded end 36, that is, the forward end of the tube 35. A pear-shaped plug 40 is also produced and placed in the expanded end 37 and concealed in place, as has been previously described, after which a helical groove 41 is produced on the tube 35 to give the proper flexibility. In this type of temple it is preferable that the inner surface should be flattened as shown at 42 in Figure 17, and this may be easily accomplished by pressing the same in a pair of heated dies.

From the foregoing it will be evident that we have provided an improved ophthalmic temple especially adapted for use in connection with imitation tortoise shell frames, which are at present so much in vogue, and also we have provided an improved method of producing such temples whereby the cost of manufacture will be comparatively low, 95 and at the same time the strength and finished appearance of the temple will be very desirable. Obviously changes may be resorted to in the form, details of construction and in the arrangement of the steps of our process, and we herein reserve the right to make such changes falling within the scope of the appended claims without departing from the spirit of our invention.

Having thus described our invention, we 105 claim:

1. A spectacle temple comprising a non-metallic tube provided with a helical groove intermediate its ends, the rear ungrooved extremity of the tube being expanded to a 110 larger cross sectional area, a shape retaining plug secured in the expanded extremity, and a metallic cord extending through the tube, said core having a flexible portion substantially coextensive with the helical groove.

115 2. The method of producing a temple, consisting in forming a non-metallic tube with an expanded extremity, inserting a plug in the expanded portion, shrinking said expanded portion over the plug, molding the extremity to desired shape, and cutting a helical groove intermediate the ends of the tube.

120 125 3. The method of producing a temple, consisting in forming a non-metallic tube with an expanded extremity, inserting a plug in the expanded portion, inserting a metallic core through the tube and anchoring same in the plug, shrinking the extremity of the tube over the core, molding it to 130

desired shape, and cutting a helical groove intermediate the ends of the tube.

4. The method of producing a temple, consisting in forming a non-metallic tube with an expanded extremity, forming a pear-shaped non-metallic plug, cementing said plug in the expanded extremity of the tube, forming a metallic core with a hinge

connection on one end, inserting the core in the tube, anchoring the extremity of the core in the plug, forming the end of the tube to conceal the plug, and cutting a helical groove intermediate the ends of the tube.
